UNITED STATES PATENT OFFICE

ALBERT STOHL, OF KOBLENZ, SWITZERLAND

TILTING CHAIR

Application filed September 4, 1928, Serial No. 303,792, and in Germany December 29, 1927.

Chairs with a tilting seat, a pivot connection between the seat and the rod carrying the seat and a spring which opposes the tilting of the seat are known. In one kind of these chairs directly underneath the seat a horizontal coil spring is arranged which is compressed on tilting the seat in the one direction, preferably in the rearward direction; a tilting of the seat in any other direction 10 however is impossible.

Further chairs are known the pedestal of which is provided with a universal joint which is positioned in a certain distance from the seat in order to enable a tilting of the seat 15 in all directions. Such chairs are not sufficiently steady especially in the raised positions of the seat, as the distance between the seat and the universal joint is then so great that at an inclination of the seat the common 20 centre of gravity of the chair and the load imposed thereon lies beyond the pedestal of the chair.

These disadvantages are eliminated by the 25 chair according to the present invention in that the pivot connection on the upper end of the rod is placed directly underneath the seat and that the spring mounting enables a tilting of the seat in at least two directions. In this arrangement no displacement of the 30 centre of gravity to speak of occurs when the seat is tilted in any direction, the chair has the same steadiness as an ordinary chair and moreover all the advantages of a tilting seat. The chair according to the invention shows 35 the further feature of simplicity in design over the known constructions.

In a preferred constructional example a 40 plate or the like is rigidly fixed to the seat and a second plate is non-symmetrically arranged relatively to the rod and pressed against the first plate by the spring surrounding the rod so that to the tilting of the seat in different directions different resist- 45 ances are opposed.

Constructional examples of the subject matter of the invention are illustrated in the drawings, in which:

Fig. 1 shows a vertical section of the tilting seat of a first constructional example.

Fig. 2 is a plan view of Fig. 3 with the seat removed.

Fig. 3 shows another constructional example in which the seat tilts in one direction only and

55

Fig. 4 shows a further constructional example provided with a universal joint in order to enable a tilting to all sides.

Fig. 5 is a vertical section of a portion of the seat together with the upper part of the rod and

Fig. 6 is a plan view of Fig. 5 with the seat removed of a further constructional example.

In the constructional example according to Figs. 1 and 2, the seat 1 is rigidly secured to the supports 2 for the seat and these supports are pivoted by means of a single pintle 4. On the rod 3 a bush 5 is displaceably arranged to which a plate 6 is screwed and which hereinafter will be designated as dished plate. Furthermore, on the rod 3 is secured a sleeve 7 provided with a screw thread to engage a threaded hand wheel 8. Between the hand wheel 8 and the dished 70 plate 6 a coil spring 9 is inserted.

In the supports for the seat, in parallel position to the pin 4, are mounted two bars 10 and 11 against which the dished plate 6 is pressed by the action of the spring 9. The tensioning of the spring 9 can be regulated 75 by means of the hand wheel 8.

If the person sitting on the seat leans backward and consequently shifts the load to the rear of the seat, i. e. towards the bar 10, the seat tilts about the pintle 4 and the bar 10 moves the dished plate 6 together with the bush 5 downwards whereby the spring 9 is compressed. A similar effect is caused by shifting the load forwards in which case it is the bar 11 which displaces the dished plate 80 together with the bush 5 relatively to the rod. Instead of the bars 10 and 11 rollers might be provided.

The constructional example according to Fig. 3 differs from the one just described in 85 that the plate 6, for instance by bending its edge portion 12 around the bar 11 is firmly secured to the latter. Thereby a tilting of the seat takes place by shifting the load towards the bar 11 as indicated by the arrow 90 100

A, a tilting of the seat in the opposite direction is impossible.

In the constructional example according to Fig. 4 instead of the pintle 4 a universal joint is provided, in that the upper end of the rod 3 has a spherical surface 13 with which cooperates a plate 14 which has a corresponding opening and which is connected to the supports 2 for the seat. The plate 6 is pressed against the plate 14 by means of a spring 9. This construction enables a tilting of the seat in every direction, the plate 6 being preferably made of circular shape, whereby the seat 1 on tilting in any direction carries out a turning movement in this direction about the spherical surface 13 and thereby displaces the plate 6 and the bush 5 together with it in the longitudinal direction of the rod against the action of the spring 9.

In all the constructional examples the inclination of the seat is limited by the distance between the hand wheel 8 and the plate 6 or the bush 5 and the sleeve 7 respectively.

The placing in the first constructional example of one of the bars 10 or 11 respectively further away from the pintle 4 than the other enables the facilitating of the tilting of the seat towards the corresponding side as the weight of the person sitting on the seat thereby acts on a greater lever arm.

In the constructional example illustrated in Figs. 5 and 6 the seat 1 is screwed on to two collateral supports 2. 3 is the rod which carries the seat and which is connected to the supports 2 for the seat by means of a cross pivot connection consisting of two pintles 4 and 5' disposed at right angles to each other. A plate 14 is further rigidly connected to the supports 2 for the seat. A plate 6 cooperates with the plate 14 and is secured to a sleeve 5 which is displaceably mounted on the rod 3. A pin 15 is arranged in the transverse direction in the rod 3 and secures the spring washer 16 in its position whereby the depending edge of the washer prevents a disengagement of the pin. The sleeve 5 has openings 17 through which the pin 15 projects. On the sleeve a hand wheel 8 is arranged which engages a screw thread on the upper portion of the sleeve 5. Between the hand wheel 8 and the washer 16 a coil spring 9 is inserted which presses the plate 6 against the plate 14. The tensioning of the spring 9 and thereby the pressure between the plates can be varied by means of the hand wheel 8.

The plate 6 is designed as a circular plate with a depending edge and is eccentrically arranged relatively to the rod. Thereby the result is attained that to the tilting of the seat in the various directions a variable resistance is opposed, as the lever arms which the load on the seat acts upon the spring vary in consequence of the unsymmetrical arrangement of the plate 6.

In Fig. 5 for instance the tilting of the

seat towards the right hand side is less resisted than the tilting to the left hand side and the plate 6 therefore ought to be arranged in such a manner that the right hand side in Fig. 5 corresponds to the rear side of the chair, as in most cases a leaning backward in the chair and a corresponding backward tilting of the seat is required to be effected in an easy manner, while an occasional forward tilting of the seat or a tilting to the sides must be opposed by a greater resistance. In the present construction, however, not only the resistance but also the angle of inclination in the different directions varies and it is particularly the backward tilting opposed by the least resistance that shows the largest angular displacement.

Instead of a circular plate 6 a polygon shaped plate might be used.

The present invention provides for a chair with a tilting seat which is adapted to be suitably tilted in various directions to a various extent, based on a simple constructional design.

I claim:

1. A tilting chair, comprising in combination, a seat, a vertical rod carrying said seat, a pivot connection between said seat and said rod, said pivot connection being arranged directly underneath the seat, a bush mounted on said rod and provided with screw thread, a hand wheel cooperating with said screw thread, and a coil spring surrounding said rod and opposing the tilting of said seat in at least two directions, said coil spring abutting against said hand wheel and the latter serving to adjust the compression of said coil spring.

2. A tilting chair comprising in combination, a seat, a rod carrying said seat, a pivot connection between said seat and said rod, said pivot connection being arranged directly underneath the seat, a spring opposing the tilting of the seat, a member rigidly connected to said seat, a second plate member pressed against the first member by the action of the spring and presenting a variable resistance to the tilting of the seat.

3. A tilting chair comprising in combination, a tilting seat, a rod carrying said seat, a pivot connection between said seat and said rod, said pivot connection being arranged directly underneath the seat, a spring opposing the tilting of the seat, a member rigidly connected to said seat, a second plate member unsymmetrically arranged relatively to the rod for the purpose of varying the amount of inclination of the seat as well as the opposition to the corresponding tilting in the various directions and pressed against the first member by the action of the spring and so arranged that to the tilting of the seat in the various directions a variable resistance is opposed.

4. A tilting chair comprising in combina-

tion, a seat, a rod carrying said seat, a pivot connection between said seat and said rod, said pivot connection being arranged directly underneath the seat, a spring opposing the tilting of the seat, a member rigidly connected to said seat, a second plate member unsymmetrically arranged relatively to the rod for the purpose of varying the amount of inclination of the seat as well as the opposition to the corresponding tilting in the various directions, a bush mounted on said rod and provided with exterior screw thread, said second plate being rigidly fixed to said bush, a transverse pin passing through said rod and serving as an abutment to the lower end of said coil spring, the latter pressing said bush and thereby said second plate against the first plate for opposing to the tilting of said seat.

5. A tilting chair comprising in combination, a central supporting rod, a pivot connecting the seat to the upper end of the rod directly beneath the seat, a plate slideable on the rod and engaging the seat, and a coil spring surrounding the rod to urge said plate against the seat and the latter into normal position.

6. A tilting chair comprising in combination, a central supporting rod, a pivot connecting the seat to the upper end of the rod directly beneath the seat, a plate slideable on the rod and engaging the seat, a coil spring surrounding the rod to urge said plate against the seat and the latter into normal position, and means at the lower end of the spring supporting said rod to adjust the tension of the spring to regulate the tilting resistance.

In testimony whereof I have signed my name to this specification.

ALBERT STOLL.
